WRAP STRIPE ATTACHMENT FOR KNITTING MACHINES

Cornelius Sherman Grove, Sr., Julius Van McKinney, and Silas Pittman, Hickory, N. C., assignors to G. and H. Hosiery Company, Inc., Hickory, N. C., a corporation of North Carolina

Application September 28, 1946, Serial No. 700,056

9 Claims. (Cl. 66—135)

1

This invention relates to a knitting machine and more especially to a wrap stripe attachment therefor.

It is an object of this invention to provide wrap stripe means associated with a circular knitting machine and having means for passing the wrap threads across the needle circle and back behind the needles after certain raised needles have engaged the wrap threads, thus wrapping the wrap threads around the needles during knitting, and providing a horn secured at one end to a bracket secured to the latch ring of the knitting machine and along which the wrap threads travel and pass off the other end of same when the needles carrying the wrap threads approach the knitting wave.

It is another object of this invention to provide in a knitting machine, a wrap stripe attachment for passing wrap threads across the needle circle and back into the inside of the needle circle so that certain raised needles will engage the wrap threads, and the wrap threads will thus be wrapped around the needles and also means are provided for raising selected needles to take the wrap threads comprising a cam adapted to be moved towards and away from the needle circle with certain of the needles having associated therewith along butt jacks, other needles which are adapted to take the wrap threads having associated therewith medium butt jacks and the other needles which do not take the wrap threads and which do conventional knitting, having short butts thereon. In this machine, only every other needle throughout the needle circle has a jack associated therewith. Means are provided, including a raising cam controlled by the pattern drum, which when advanced fully towards the needle circle, engages the long butt and medium butt jacks, and raises selected spaced needles to take the wrap threads for the entire travel of the needle circle; that is, to form wrap stripes at spaced intervals entirely around the stocking. During heel and toe knitting, it is, of course, evident that the wrap stripes should not extend through the heel and the sole of the stocking. The medium butt jacks are provided for controlling the needles on one-half of the needle circle, so that when the raising cam is moved to midway or intermediate position, it will not raise the wrap needles having the medium butt jacks associated therewith, but will raise the long butt jacks to raise the wrap needles occurring on the front portion of the stocking so that the wrap stripes will extend down on top of the foot of the stocking, but will not extend through the heel and sole portion of the stocking.

It is another object of this invention to provide a wrap stripe attachment for circular knitting machines having means for passing wrap threads across the needle circle to cause certain

2

raised needles to engage the wrap threads to form wrap stripes in the fabric being knitted and having an arcuate horn shaped member along which the wrap threads travel until they almost reach the knitting wave from whence the wrap threads pass off the end of the horn, said horn being attached to the bracket which holds the clamp and cutter plate and extending downwardly and then extending in an arc of a circle immediately inside the needles, said machine having a clamp and cutter plate associated therewith having a guide finger on one end which extends upwardly and over the end of the horn from whence the wrap threads pass in a knitting operation and the other end of the clamp and cutter plate extending below and in spaced relation to the horn but extending to the outer edge of the horn, so that during reciprocatory knitting, the wrap threads cannot pass above the clamp and cutter plate but on account of the pointed end of the clamp and cutter plate passing beneath the horn a substantial distance, it will cause the wrap threads guided by the horn, during back and forth knitting, to be confined by the horn and clamp and cutter plate, and will not pass on top of the clamp and cutter plate.

Some of the objects of the invention having been stated, other objects will appear as the description proceeds when taken in connection with the accompanying drawings, in which

Figure 1 is an elevation of the upper portion of a knitting machine commonly termed a Scott and Williams B-5 machine and showing the wrap stripe attachment mounted thereon;

Figure 2 is a sectional plan view taken substantially along the line 2—2 in Figure 1;

Figure 3 is a sectional plan view taken substantially along the line 3—3 in Figure 1 and showing much of the structure shown in Figure 2 but on an enlarged scale and showing only the central portion thereof;

Figure 4 is a sectional and elevational detail of the lower end of the wrap shaft showing the disk and tubes associated therewith, and taken along the line 4—4 in Figure 3;

Figure 5 is a sectional view taken along the line 5—5 in Figure 3;

Figure 6 is a view similar to Figure 5, but showing the wrap shaft and disk in raised position, and showing the gap closer moved to a different position;

Figure 7 is an exploded view of the needle circle looking from the inside thereof but not showing the full number of needles for sake of clearness;

Figure 8 is a sectional view taken along the line 8—8 in Figure 2;

Figure 9 is a sectional view taken along the line 9—9 in Figure 1;

Figure 10 is a sectional view through the support bracket and through the wrap shaft disk;

Figure 11 is a schematic view, in plan, of the needle jacks.

Referring more specifically to the drawings, the numeral 10 indicates the bed plate of a knitting machine having the tubular portion 11 extending downwardly therefrom. The bed plate is an annular member and has mounted for rotation therein a needle cylinder having a plurality of needles mounted in vertically disposed grooves therein. This cylinder is driven by conventional means such as a bevelled gear 13 located on the main shaft 14 and meshing with a horizontally disposed bevelled gear, not shown, affixed to the cylinder. The main shaft 14 also has a bevelled gear 16 mounted thereon which meshes with a bevelled gear 17 on a shaft 18 which projects upwardly and drives the wrap stripe mechanism which will be presently described.

In the drawings we have shown certain spaced needles 131 which have medium butt jacks M associated therewith and certain other spaced needles 131 having long butt jacks L associated therewith and the remainder of the needles 131 have short butt jacks S associated therewith. Of course, in this type of machine only every other one of the needles will have a jack associated therewith as the other needles 130 will have their conventional butts which will be raised and lowered in a conventional manner by conventional cams. The purpose of these different length jacks will be explained later in this application.

The knitting machine has a conventional sinker ring 20 associated therewith having conventional sinkers, not shown, mounted therein and which project between the needles in a conventional manner for holding the loops on the needles and preventing the loops being raised by the needles. The machine also has a conventional latch ring 21 pivoted as at 22, and it also has a plurality of yarn feed fingers 23 which operate in a conventional manner. Mounted within the latch ring is a gap closer ring 24 which is oscillatable by means of a link 26 having its other end connected to a lever 27 which is operated in a conventional manner by the main pattern drum. The gap closer ring is held in normal operating position so as not to close the throat gap during circular knitting by means of a tension spring 30 anchored at one end to the lever 27 and at its other end to a spring perch 31 secured to the exterior of the latch ring.

The latch ring has a projecting portion 33 which is adapted to engage a leaf spring 34 mounted on a bracket 35 extending upwardly from the bed plate 10 for holding the latch ring in lowered or operating position.

The latch ring has secured thereto a bracket 40 which is secured to the projecting portion 33 of the latch ring and extends upwardly and then inwardly to a point about centrally of the needle circle and has secured to the lower surface thereof centrally of the needle circle by means of a shaft 39 a clamp and cutter plate 41 which has a conventional spring clamp 42 and a pivoted clamp 43 and a cutter mechanism 44 which are conventional and are operated by a link 45 having its upper end pivoted to a lever 47 pivoted on a shaft 48 and is operated by a conventional push rod engaging the outer end thereof and which push rod is not shown but is controlled by the main pattern drum.

The lever 47 has projecting upwardly therefrom an arm 51 which is adapted to engage the horizontal portion of an arm 52 having its lower end secured as at 53 in a crank member 54 piv-

oted as at 55 and having a cam portion 56 on its free end adapted to be engaged by a cam on a disk on the wrap stripe shaft which will be presently described to operate the clamp and cutter upon each revolution of the wrap shaft.

The bracket member 40 also has extending downwardly therefrom a shaft 60 which is secured also to the clamp and cutter plate 41 for assisting in supporting the clamp and cutter plate. The bracket 40 centrally of the clamp and cutter plate rises upwardly and then laterally, and has a bearing portion 64 associated therewith in which a bushing 65 is rotatably mounted. This bushing 65 has an enlarged portion 66 secured on its upper end which is adapted to rest on top of the bearing 64. The bushing 65 has a plurality of vertically disposed bores 67 therein through which the wrap threads W pass on their travel from the yarn packages 98 to the needles.

Integral with the lower end of the bushing 65 is a bevelled gear 70 through which the bores 67 extend. The wrap shaft 72 has a key 73 therein and the bushing 65 has a key-way 74 therein which allows up and down movement of the wrap shaft 72. The bevelled gear 70 has meshing therewith a bevelled gear 75 which is mounted on a shaft 78 rotatably mounted in a portion 76 of the bracket 40 and this portion 76 extends downwardly and is secured to a projecting portion of the latch ring as at 77.

Secured on the shaft 78 is another bevelled gear 80 which meshes with a bevelled gear 81 secured on the upper end of the shaft 18. The shaft 18 is mounted in a tubular uprising member 84 and in which it rotates. The outer end of the shaft 78 is rotatably mounted in a bearing portion 86 which is integral with the horizontally disposed portion 83 of the bracket 40. An outwardly projecting portion 88 of the uprising tubular member 84 has mounted therein a set screw 89 which engages the lower surface of the portion 86 and limits the downward movement of the bracket and the latch ring when they are moved to operating position. The portion 86 has a leaf spring member 90 mounted thereon which projects downwardly and has a suitable hole therein adapted to engage a pin 91 on the outwardly projecting portion 88 to assist the leaf spring 34 in locking the latch ring in operating position.

The downward movement of the wrap shaft 72 is limited by a collar 94 secured on the wrap shaft immediately above the flange 66 by any suitable means such as set screw 95. The wrap shaft 72 has mounted thereon a circular table 96 on which a plurality of pins 97 are mounted for holding cops of wrap yarn 98. This disk or table has in its hub portion 93 a plurality of vertically disposed eyelets 99 through which the wrap threads W pass.

On the upper end of the wrap shaft 72 is mounted a plate 100 having a plurality of arms 101 and each arm having an eyelet 102 therein through which a wrap thread passes upwardly and goes through a suitable tension device 103 mounted on an uprising portion 104 and on the upper end of portions 104 are mounted the take-up arms 105 through which the wrap yarns also pass, said take-up arms being biased towards upraised position by means of a tension spring 107. The hub portion 109 of the plate 100 has a plurality of vertically disposed eyelets through which the wrap threads pass in their downward movement. Before they pass through these

eyelets, however, they pass beneath a ring 108 supported just outside of the hub portion 109 of the plate 100.

Mounted on wrap shaft 72 and below the bearing 64 is a disk 110 having a plurality of vertically disposed passageways 111 therein through which the wrap threads pass in their downward travel to the needles. This disk 110 has a cam 112 thereon adapted to engage the pointed end 56 of the lever 54 for operating the clamp and cutter mechanism upon each revolution of the wrap shaft when the wrap shaft is in lowered position.

Immediately below the disk 110 and on the lower end of the wrap shaft 72 is a wrap disk 115 having a plurality of vertically disposed tubes 116 therein through which the wrap threads W pass in their downward travel and said tubes being adapted to move across the needle circle, since the wrap shaft 72 is mounted eccentrically with respect to the center of the needle circle, but its vertical axis is at a point within the needle circle.

Pivoted on shaft 48 is a lever 114 whose front end extends below the disk 110 and its rear end has a pin 117 engaged by a lever 118, pivoted at 119 and whose rear end is raised and lowered by a conventional push rod 123 controlled by the main pattern drum. Mounted on the bracket 49 by means of screws 180 is a shank portion 120 of a substantially semi-circular horn 121 which extends around inside the needle circle in close proximity to the needles to a point immediately past the throat gap of the machine. This horn is disposed slightly above the clamp and cutter plate, but the clamp and cutter plate has a pointed portion 124 which extends to approximately flush with the outer surface of the horn but is disposed below and in spaced relation to the horn Figure 5 and thus prevents the wrap threads from getting above the clamp and cutter plate during reciprocatory knitting. The clamp and cutter plate 41 has a guide 46 extending upwardly and above the horn 121 for guiding the wrap yarns under the clamp and cutter plate. Plate 41 has an upturned finger 9 projecting above the end of horn 121 to guide the wrap yarns beneath the clamp and cutter plate 41. The guide finger 46 as well as clamp 42 are secured to the clamp and cutter plate 41 by means of a screw 49.

It is understood that this machine is usually equipped with a conventional rubber feed attachment for feeding an elastic yarn to the needles especially during the knitting of the top section, but such rubber attachment is not shown for sake of clearness.

In Figure 7 an exploded view of the needle circle is shown looking from the inside thereof and, although not as many needles are present as would be in a conventional knitting machine cylinder, it is shown for illustrative purposes only. In Figure 7 we show the knitting cams 125, 126, and 127, and 128, which are conventional and explanation is not deemed to be necessary.

We show certain spaced needles 130, which are the conventional knitting needles which do not have any jacks associated therewith but whose butts can be long, short or medium, and are controlled by conventional cams, not shown. Alternately disposed between these conventional needles having no jacks associated therewith, are a plurality of needles 131. Some of these needles 131 have long butts jacks L associated there-

with while others of the needles have medium butt jacks M associated therewith. These long and medium butt jacks are adapted to be engaged by a raising cam 135 for raising the long butt jacks L and the medium butt jacks M.

The cam 135 has affixed thereto a stem 137 which is slidably mounted in a bracket 138 mounted on top of the bed plate 10 of the machine. The bracket 138 has a slot 140 on its upper side and a pin 141 is affixed to the shank 137 and has a tension spring 142 secured thereto whose other end is secured to a spring perch 143 secured on top of the bed plate 10. This normally tends to hold the cam 135 out of the path of either the long or medium butt jacks L and M. Adapted to engage the outer end of the portion 137 is a set screw 145 mounted in an upturned portion 146 on the end of a lever 147 pivoted as at 148 and supported at its other end by a guide 150 disposed thereabove to assist the lever 147 in withstanding the upward thrust of a push rod 152 which is raised by the conventional main pattern drum of the machine.

The push rod 152 has a cut-away portion 160 which is adapted to coincide with lever 147 when the push rod 152 is not resting on any cams on the main pattern drum. This push rod 152 also has a cammed surface 162, which when the push rod 152 is raised upwardly by a low cam on the main pattern drum, causes the lever 147 to be oscillated to advance the cam 135 inwardly to the point where it will engage the long butt jacks L only to raise those groups of needles associated therewith for taking the wrap threads. This position is maintained during the knitting of the heel and during the knitting of the foot out to the toe portion and this prevents any wrap stripes from being formed in the heel and sole portion of the stocking.

When the push rod 152 has ridden onto a high cam on the main pattern drum, it will cause a cammed portion 164 to engage the lever 147 and advance the cam 135 inwardly to its greatest extent which will cause it to engage not only the long butt jacks L but also the medium butt jacks M to raise both the long and medium butt jacks which will cause the wrap stripe needles all the way around the needle circle to be raised to form wrap stripes not only in the front portion of the stocking but also in the back portion of the leg of the stocking.

In order to traverse the needle circle with the tubes 116, it is desirable to cut away a portion of the latch ring to form a cavity at 170. There is, of course, danger of needle latches becoming opened and, if they fell into this cavity during knitting, they might be broken unless some provision were made to prevent such. We find it is not necessary to close this cavity 170 in the latch ring but in the gap closer ring, we cut away certain portions thereof leaving a portion 171 with cammed surfaces 172 and 173 on opposed edges thereof, which will engage any needle latches which might fall to open position while passing the cavity 170. We also cut away all of the vertical portion of the gap closer ring extending from the cammed surfaces 173 over to a cammed surface 175. These cammed surfaces serve to open or close the partially opened latches of any needles which pass thereby.

By this arrangement it is possible to cut whatever size of cavity as may be necessary in the latch ring, and it is not necessary to close this cavity because the cam surfaces 172, 173, and 175 insure that the needle latch will be moved to

fully opened or fully closed position if they should be partially opened in passing by this cavity 170.

In the drawings and specification, there has been set forth a preferred embodiment of the invention, and although specific terms are employed, they are used in a generic and descriptive sense only and not for purposes of limitation, the scope of the invention being defined in the claims.

We claim:

1. In a circular knitting machine, having a bed plate, a pattern drum, a latch ring, and a throat gap, and a circular series of needles, spaced needles disposed at intervals around a portion of the circle and having long butt jacks associated therewith, other spaced needles disposed around another portion of the circle and having medium butt jacks associated therewith, an elevating cam for engaging said butts and raising the same, means for advancing the cam fully inwardly to raise both the long butt and medium butt jacks for raising the same, means for advancing the cam inwardly to a lesser amount to engage and raise only the long butt jacks, and means for feeding wrap threads to the needles raised by their associated jacks, the means for advancing the cam fully inwardly and the means for advancing the cam inwardly a lesser amount comprising a push rod movable by the pattern drum, a lever mounted on the bed plate and having one end engaging the cam for moving it inwardly and having its other end engageable by the push rod, and such rod having one cam portion for engaging said lever and moving it to move the cam partially inward to engage only the long butt jacks and having another cam portion for engaging the said lever and moving the cam further inwardly to engage both the medium butt jacks and the long butt jacks.

2. In a circular knitting machine, having a latch ring, and a throat gap, and a circular series of needles, spaced needles disposed at intervals around a portion of the circle and having long butt jacks associated therewith, other spaced needles disposed around another portion of the circle and having medium butt jacks associated therewith, an elevating cam for engaging said butts and raising the same, means for advancing the cam fully inwardly to raise both the long butt and medium butt jacks for raising the same, means for advancing the cam inwardly to a lesser amount to engage and raise only the long butt jacks, a vertically disposed rotary wrap shaft disposed above the needle circle and mounted eccentrically to the needle circle and having a plurality of yarn feed tubes extending downwardly from its lower end, each carrying a wrap thread and being adapted to move across the needle circle to place wrap threads in front of the raised needles, a bracket secured to the latch ring and in which the wrap shaft is rotatably mounted, a wrap horn secured to the bracket and extending downwardly inside the needle circle and having an arcuate portion extending past the throat of the machine and along which and off the end of which the wrap threads pass, a clamp and cutter plate secured to said bracket and disposed within the needle circle and having a guide finger for wrap yarns on one end extending above and in spaced relation to the free end of the horn and having a pointed portion extending below and in spaced relation to the other end of the horn.

3. In a circular knitting machine, having a throat with yarn feed fingers and latch ring,

means for raising a plurality of sets of spaced needles to take wrap threads, an eccentrically disposed wrap disk having downwardly projecting feed tubes and mounted to rotate on a vertical axis disposed eccentrically to the needle circle and adapted to cross the needle circle to place wrap threads in front of certain raised needles, cam means for raising the spaced needles to take wrap threads, means for advancing the cam to raise same but not all of the spaced needles and also for further advancing the cam to raise all of the spaced needles to take wrap threads, a bracket mounted on the latch ring for rotatably supporting the wrap disk, an approximately semi-circular clamp and cutter plate disposed below and secured to the bracket, a horn secured to the bracket and extending downwardly inside the needle circle and extending horizontally to a point adjacent the throat gap and along which the wrap threads pass, said clamp and cutter plate having a finger on one end extending above the free end of the horn for guiding the wrap threads beneath the clamp and cutter plate, said plate having a pointed portion at its other end extending beneath the base portion of the horn to prevent wrap yarns from passing onto the top of the plate during reciprocatory knitting.

4. In a circular knitting machine having a plurality of needles arranged in a circle and having a latch ring with a throat gap in which yarn feed fingers are mounted, certain spaced needles having long butt jacks and other spaced needles having medium butt jacks, means for feeding wrap strands across the needle circle, cam means operable to raise only the needles having long butt jacks to cause them to take the wrap strands, said cam means also being operable to also raise the needles having medium butt jacks to cause all spaced needles to take the wrap strands, a bracket mounted on the latch ring for supporting the wrap strand feeding means, a clamp and cutter plate disposed within the needle circle, and supported by the bracket, a horn having one end secured to said bracket, and extending downwardly inside the needle circle, and then extending in a horizontal direction adjacent the needles to the throat gap and along which the wrap strands pass, said clamp and cutter plate having on one end a wrap strand guiding finger extending above the free end of the horn and having a finger on the other end thereof extending beneath the horn for preventing wrap strands from passing above the plate during reciprocatory knitting.

5. In a circular knitting machine, having a latch ring, means for feeding wrap strands across the needle circle, means for selectively raising some of the needles to take the wrap strands, a substantially semi-circular clamp and cutter plate disposed within the needle circle, an arcuate horn disposed within the needle circle and along which the wrap strands move, means for securing one end of the horn to the latch ring, one end of the plate having a finger projecting above the free end of the horn and the other end of the plate projecting below the base portion of the horn.

6. In a circular knitting machine having a latch ring and a cylinder in which a plurality of needles is mounted for vertical movement, and having a bed plate in which the cylinder is mounted for rotation, certain spaced needles having long butt jacks associated therewith, and other spaced needles having medium butt jacks associated therewith, a cam for raising the long

and medium butt jacks, said machine having push rods operable by a conventional pattern drum, a lever mounted on the bed plate and having one end engaging the cam for moving it inwardly and outwardly, a push rod for engaging the other end of said lever, said push rod having one cam portion for engaging the other end of the lever for advancing said cam to a point where it will engage only the long butt jacks to raise the spaced needles associated therewith, the push rod having another cam portion for engaging the lever to move the cam further inwardly towards the needle cylinder to also raise the medium butt jacks, means disposed above the needle circle for feeding wrap yarns to the spaced raised needles.

7. In a circular knitting machine having a latch ring and a cylinder in which a plurality of needles is mounted for vertical movement, and having a bed plate in which the cylinder is mounted for rotation, certain spaced needles having long butt jacks associated therewith and other spaced needles having medium butt jacks associated therewith, a cam for raising the long and medium butt jacks, said machine having push rods operable by a conventional pattern drum, a lever mounted on the bed plate and having one end engaging the cam for moving it inwardly and outwardly, a push rod for engaging the other end of said lever, said push rod having one cam portion for engaging the other end of the lever for advancing said cam to a point where it will engage only the long butt jacks to raise the spaced needles associated therewith, the push rod having another cam portion for engaging the lever to move the cam further inwardly toward the needle cylinder to also raise the medium butt jacks, means disposed above the needle circle for feeding wrap yarns to the spaced raised needles, a bracket mounted on the latch ring for supporting the means for feeding wrap yarns, a horn member having a free end and a base portion, means for securing the base of the horn to the bracket, said horn extending from its base portion downwardly inside the needle circle and along the needles for approximately a semi-circle, a clamp and cutter plate mounted on the bracket and disposed within the needle circle a finger on one end of the plate extending above the free end of the horn for guiding wrap yarns below the plate, the other end of the plate extending below the base portion of the horn for preventing the wrap yarns from passing on top of the plate during reciprocatory knitting.

8. In a circular knitting machine having a cylinder with a plurality of needles and having a latch ring and a bed plate in which the cylinder is mounted for rotation, means disposed above the needle circle for feeding wrap yarns to the needles, some of the needles having long butt jacks associated therewith and other needles having medium butt jacks associated therewith and other needles having short butt jacks associated therewith, a cam for engaging the jacks for raising the needles associated therewith, a lever mounted on the bed plate and having one end thereof engaging the cam, said machine having conventional pattern controlled push rods, one of the push rods having a cam surface on its upper end for engaging the other end of the lever when raised by the

pattern drum for advancing the jack raising cam to engage only the long butt jacks to raise the needles associated therewith to take the wrap yarns, said push rod having another cam surface thereon for engaging the other end of the lever and further advancing the jack raising cam to raise also the medium butt jacks and the needles associated therewith.

9. In a circular knitting machine having a cylinder with a plurality of needles and having a latch ring and a bed plate in which the cylinder is mounted for rotation, means disposed above the needle circle for feeding wrap yarns to the needles, some of the needles having long butt jacks associated therewith and other needles having short butt jacks associated therewith, a cam for engaging the jacks for raising the needles associated therewith, a lever mounted on the bed plate and having one end thereof engaging the cam, said machine having conventional pattern controlled push rods, one of the push rods having a cam surface on its upper end for engaging the other end of the lever when raised by the pattern drum for advancing the jack raising cam to engage only the long butt jacks to raise the needles associated therewith to take the wrap yarns, said push rod having another cam surface thereon for engaging the other end of the lever and further advancing the jack raising cam to raise also the medium butt jacks and the needles associated therewith, a bracket mounted on the latch ring for supporting the wrap yarn feeding means, a clamp and cutter plate supported by the bracket and disposed within the needle circle, a horn mounted on the bracket and extending downwardly inside the needle circle and then extending horizontally adjacent the inside of the needle circle for supporting the wrap threads and off the free end of which the wrap yarns pass, the clamp and cutter plate having a finger on one end extending above the free end of the horn for guiding wrap yarns beneath the clamp and cutter plate, the other end of the clamp and cutter plate having a pointed portion extending beneath the base portion of the horn for preventing wrap threads from passing onto the top of the clamp and cutter plate during reciprocatory knitting.
